METHOD AND APPARATUS FOR MAKING
AIR INSULATED CABLE

Hans D. Isenberg, Wilmette, Ill.

Application February 3, 1945, Serial No. 576,079

11 Claims. (Cl. 57—6)

1

The present invention relates to methods and apparatus for making air insulated or coaxial cable and more particularly to improved methods and apparatus for continuously forming an insulating supporting structure upon the inner conductor of a coaxial cable. This application is a continuation-in-part of applicant's copending application Serial No. 487,990, filed May 22, 1943, now Patent 2,395,872, granted March 5, 1946.

Coaxial cable of the type used commercially in wide band high frequency circuits is conventionally comprised of two coaxially arranged conductors which are held apart by insulating discs provided at spaced points along the two conductors to support the inner conductor centrally within the outer conductor and thus provide a dielectric air space therebetween. Manual methods are usually employed in assembling the discs upon the inner conductor and within the outer conductor. This is not only costly, but requires that the cable be formed in relatively short lengths or sections which must be joined in order to obtain a cable of any considerable length.

It is an object of the present invention, therefore, to provide improved methods and apparatus for continuously forming an air insulated or coaxial cable of any desired length.

It is another object of the invention to provide an improved method for the purpose described, which requires a minimum of manual labor in the practice thereof and may be utilized to produce completed cable at a high production rate.

It is a further object of the invention to provide improved and exceedingly simple apparatus which is positive and reliable in its operation to produce air insulated cable continuously and at a high production rate.

It is still another and more specific object of the invention to provide improved methods and apparatus for forming around a continuously moving conductor an insulating supporting structure upon which an outer conductor or covering may be wrapped to provide an air insulated cable.

The invention, both as to its organization and method of operation, together with further objects and advantages thereof, will best be understood by reference to the following specification taken in connection with the accompanying drawings, in which:

Fig. 1 is a view schematically illustrating improved apparatus for continuously making air insulated cable, which is characterized by the features of the present invention;

Fig. 2 is a side view partially in section, illustrating a segment of the cable produced by use of the apparatus shown in Fig. 1; and

Fig. 3 is an end sectional view taken along the lines 3—3 in Fig. 2.

Referring now to the drawings and more particularly to Fig. 1 thereof, the present improved air insulated or coaxial cable as disclosed in Figs. 2 and 3, and in the above referred to copending application, is made by forming a continuous filamentary element 11 of plastic insulating material into helical convolutions 13 disposed along the length of the inner conductor 12 of the cable, and utilizing a cylindrical reciprocating mandrel 20, through which the inner conductor 12 is fed, to so vary the diameter of the helical convolutions 13 that certain thereof, i. e., the convolutions 13a are radially spaced from the conductor to support the outer sheath 21, and others thereof, i. e., the convolutions 13b, engage the conductor 12 at spaced points along the length thereof to support the radially spaced convolutions 13a from the conductor.

More specifically considered, the convolution forming mandrel 20 is slidably supported within the sleeve portion 30a of a fixed support 31 and is provided with a tapered central bore 21 through which the inner conductor 12 is fed from a supply spool 16 over a rotatably supported guide roll 19. This mandrel also extends within the sleeve portion 30a of a rotatable feeding element or table 30 which is supported upon the upper surface of the supporting member 31 by means of ball bearings 32. Adjacent the periphery thereof, the feed table 30 carries an angularly disposed post 29 upon which a supply spool 28 for the filamentary element 11 of insulating material is rotatably supported. The element 11 is carried through a feed eye 30b provided at the end of an arm 30c which is anchored to the sleeve portion 30a of the feed table 30. Thus the entire filament feed assembly comprising the rotatable table 30 and the supply spool 28 is rotatable around the conductor 12 as it emerges from the upper end of the mandrel 20.

For the purpose of reciprocating the mandrel 20 so that the filamentary element 11 is alternately wound around the upper cylindrical end thereof and directly around the conductor 12, this mandrel is provided at its lower end with a rotatably supported cam following roller 24 biased into peripheral engagement with a rotatable cam 25 by means of a coil spring 24a reacting between the supporting member 31 and a washer-like disc 24b fixed to the lower end of the mandrel. The upper end of this mandrel is of conical configuration such that the diameter of those convolutions 13b, disposed between the adjacent groups of radially spaced convolutions 13a

of uniform diameter, is gradually increased and decreased.

In order spirally to wrap the outer sheath 27 of material about the helical convolutions 13, thereby to complete the formation of the cable, a second winding or wrapping assembly is provided which comprises a table 38 rotatably supported by means of ball bearings 40 upon a fixed supporting member 39. Adjacent its peripheral edge this table fixedly carries an angularly disposed post 37 upon which is rotatably mounted a supply spool 36 for the strip material 35, conductive or insulating, from which the outer sheath 27 of the cable is formed. Movement of the conductor 12 through the mandrel 22 is effected by drawing the completed cable 10 between a pair of rollers 14 and 15, the first of which is free to rotate about its supporting axis, and second of which is adapted to be driven at a suitable speed through a driving connection 17 from a drive mechanism 16.

This mechanism is also utilized to drive the rotatable feed table 30 through a driving connection 34 and a gear 33 engaging the toothed periphery of the table 30. It is also utilized to drive the table 38 through a peripherally engaging gear 41 and a driving connection 42, and to rotate the cam shaft 26. In this regard it is noted that the speeds of rotation of the rotatable elements 14, 38, 30 and 26 are definitely inter-related within the drive mechanism 16 so that each element is operated in a predetermined timed relationship with respect to the operation of the other elements.

Preferably the filamentary element 11 from which the helical convolutions 13 are formed is comprised of a flat strip of thermo-setting or thermo-plastic material which has the property of being settable in a fixed configuration either when heated to a predetermined temperature or when heated to a semi-plastic state and then cooled. Specifically, this element may be formed of a phenolic resin material, a methyl methacrylate resin, a vinyl chloride acetate resin, a polystyrene resin, or a polyvinyl chloride resin material. It may be of any desired cross-sectional configuration although preferably is round or oval, in order to provide a hair line contact of the strip with the conductor 12 and thus reduce the dielectric losses and capacitance between the conductor and the outer sheath 27. For the purpose of heating this element to a temperature which will cause permanent and unstressed setting thereof in the desired helical configuration, facilities are provided for inductively heating the mandrel 20 about which the radially spaced convolutions 13a are formed. These facilities comprise a small coil 43 disposed within the mandrel and having its terminals brought out to opposite output terminals of a high frequency current source 44 through the bore of the mandrel. This source may have an output frequency of the proper value to insure rapid and continuous heating of the external surfaces of the mandrel 20.

Briefly to consider the manner in which the above described apparatus is utilized in practicing the present improved method of making the cable shown in Fig. 2 of the drawings, it will be understood that with the drive mechanism 16 operating, the roller 14 is driven to draw the cable 10, as completed, between this roller and the roller 15, thereby to pull the inner conductor 12 through the mandrel 20. In this regard it is noted that shortly before operation of the drive mechanism is initiated, the high frequency current source 44

should be activated in order that the mandrel may be inductively heated by the coil 43 to the required temperature for insuring a permanent set of the filamentary element 11 in the desired helical configuration. Immediately operation of the drive mechanism 16 is initiated, this mechanism, in addition to driving the roller 14, also functions to rotate the feed table 30 about the axis of the mandrel 20, to rotate the table 38 about the same axis, and to rotate the cam 25 with its drive shaft 26. As the feed element 30 is rotated around the mandrel 20, the filamentary element 11 of plastic insulating material is withdrawn from the supply spool 28 and wound around the conductor 12 to produce the helical convolutions 13. Assuming that the parts of the apparatus occupy their illustrated positions at the time operation of the apparatus is initiated, the cam 25, which is driven in a counterclockwise direction from the illustrated position thereof, coacts with the roller 24 gradually to move the mandrel 20 upward through the sleeve portion 30a of the feed table 30. As the mandrel is moved upward past the feed eye 30b, the filamentary element 11 gradually climbs up the conical end 22 of the mandrel to gradually increase the diameter of the convolutions formed by winding the element 11 around the conductor 12. More specifically, the relative rotary speeds of the cam 25 and the feed table 30 are preferably such that the filament 11 climbs to the outer cylindrical surface of the mandrel 20 during the formation of approximately one-half of one convolution. During continued rotation of the cam 25, the mandrel 20 is increasingly advanced through the sleeve portion 30a of the element 30 so that the filamentary element 11 is wound around the outer cylindrical surface of this mandrel to form spaced helical convolutions therealong. Incident to the formation of these convolutions, the material from which the element 11 is formed is heated above the critical temperature required for permanent setting thereof in the desired helical configuration. When the cam 25 is advanced to bring the point 25a beneath the roller 24 and during continued rotation of the cam, the mandrel 20 is retracted to its starting position under the influence of the biasing spring 24a. Incident to this return movement of the mandrel to its start position, the formed convolutions 13 wound around the upper cylindrical end thereof engage the upper end of the sleeve 30a and are pushed off the mandrel to assume positions spaced along the conductor 12. During final movement of the mandrel back to its starting position, the element 11 is again wound around the conical end 22 of the mandrel to decrease the convolution diameter. Finally, and when the mandrel 20 reaches its fully retracted position, the upper end thereof is so disposed that the filamentary element 11 is wound directly around the inner conductor 12 of the cable to form the supporting convolutions 13b. It will be apparent that by properly relating the short uniform radius portion of the cam 25 to the variable radius portions thereof and to the speed of rotation of this cam and the speed of rotation of the feed element 30, one or more complete convolutions 13 may be wound directly around the conductor 12 as this conductor advances through the mandrel 20. From this point on, the described cycle of operations is repeated on an indefinite basis so long as the drive mechanism 16 is maintained in operation.

From a consideration of Figs. 2 and 3 of the drawings, it will be noted that the resulting insu-

lating supporting structure comprises spaced groups of convolutions 13a of equal diameter which are radially spaced from the inner conductor 12 and are alternated with convolutions 13b which tightly embrace the conductor 12 and serve to support the radially spaced convolutions 13a from this conductor. It will also be understood that since the thermo-plastic or thermo-setting filamentary element 11 is heated to its setting or annealing temperature incident to the formation of the convolutions, a permanent set is imparted to the convolutions 13 which enhances the tendency of these convolutions to reassume the formed positions thereof when distortion pressures imposed thereon are relieved.

Concurrently with formations of the helical convolutions 13 in the manner just described, the outer sheath 27 of insulating or conducting material is progressively wound around the convolutions 13 to complete the cable structure. This is accomplished through rotation of the table 38 to rotate the strip supply spool 36 around the conductor 12. Incident to such rotation the strip 35 of insulating or conducting material is withdrawn from the spool 36 and wound in edge overlapping relationship around the conductor 12 tightly to embrace the outer surfaces of the radially spaced convolutions 13a. This strip material is preferably self-adhering so that the overlapped edges thereof are bonded to prevent separation after the cable is completed. The strip 35 may be formed of tape or foil material or of a suitable braid. It may also be composed of a wound or braided conductor consisting of conductive and insulating strands. Preferably, the table 38 is rotated in a direction opposite to the direction of rotation of the feed table 30, such that the direction of spiral of the strip 35 is opposed to the direction of spiral of the filamentary element 11. Opposed spiralling of the element 11 and the strip 35 enhances the supporting action of the convolutions 13 and thus serves to enhance the rigidity of the completed cable structure. As the completed cable 10 is withdrawn through the rollers 14 and 15 it may be coiled, or wound upon a suitable takeup reel for shipment.

From the foregoing explanation, it will be understood that the number of radially spaced convolutions 13a formed between each pair of spaced supporting convolutions 13b depends upon the relative speeds of the feed table 30 and the cam 25. By appropriately changing the relationship between these speeds within the drive mechanism 16, any desired number of convolutions 13a may be formed between each adjacent pair of supporting convolutions 13b. It will also be apparent that the rapidity with which the diameter of the convolutions 13 is increased and decreased between the diameter of the conductor 12 and the diameter of the mandrel 20 depends in part upon the configuration or length of the conical mandrel end 22. By properly relating this factor to the selected operating speed of the table 30, any desired rate of convolution diameter change can be obtained.

It should be understood that the expression "air insulated cable" used throughout this specification and in the appended claims is a generic expression and refers to gaseous insulation as distinguished from solid insulating materials. It is intended that the expression include gases other than air such as the individual components of air; for example, nitrogen or other gases.

While there has been described what is at present considered to be the preferred embodiment

of the invention, it will be understood that various modifications may be made therein which are within the true spirit and scope of the invention as defined in the appended claims.

5 I claim:

1. Apparatus for making cable having an inner conductor, comprising means for continuously moving said conductor longitudinally thereof, means operated in timed relationship with said last-named means for continuously winding a filamentary element of insulating material around said conductor to form helical convolutions spaced along the length of said conductor and surrounding said conductor, and means operated in timed relationship with said last-named means for so controlling the winding of said convolutions that certain thereof are radially displaced from said conductor and the other convolutions engage said conductor at spaced points along the length thereof to support said certain convolutions from said conductor.

2. Apparatus for making cable having an inner conductor, comprising a cylindrical convolution forming mandrel, means for continuously moving said conductor through said mandrel, means operated in timed relationship with said last-named means for continuously winding a filamentary element of insulating material to form helical convolutions spaced along the length of said conductor and surrounding said conductor, and means operated in timed relationship with said last-named means for so moving said mandrel that said convolutions are formed by alternately wrapping said strip around said mandrel and directly around said conductor, whereby the convolutions formed by wrapping said strip around said mandrel are spaced radially from said conductor and the convolutions formed by wrapping said strip directly around said conductor serve to support said radially spaced convolutions from said conductor.

3. Apparatus for making cable having an inner conductor, comprising a cylindrical convolution forming mandrel, means for continuously moving said conductor through said mandrel, feeding means operated in timed relationship with said last-named means and rotatable around the axis of said mandrel for continuously winding a filamentary element of insulating material around said conductor to form helical convolutions spaced along the length of said conductor and surrounding said conductor, and means operated in timed relationship with said feeding means for so reciprocating said mandrel back and forth axially thereof that the predominant portion of said convolutions are formed by wrapping said strip around said mandrel and the remaining portion of said convolutions are wrapped directly around said conductor, whereby the convolutions formed by wrapping said strip around said mandrel are spaced radially from said conductor and the convolutions formed by wrapping said strip directly around said conductor serve to support said radially spaced convolutions from said conductor.

4. Apparatus for making air insulated cable having an inner conductor, comprising a cylindrical convolution forming mandrel having a conical end, means for continuously moving said conductor through said mandrel, feeding means operated in timed relationship with said last-named means for continuously winding a filamentary element of insulating material around said conductor to form helical convolutions spaced along the length of said conductor, and means

operated in timed relationship with said strip feeding means for so moving said mandrel that at least the conical end thereof is moved into and out of said convolutions incident to the formation thereof, thereby to so change the diameter of said convolutions that the predominant portion thereof are radially spaced from said conductor.

5. Apparatus for making cable having an inner conductor, comprising means for forming a continuous filamentary element of heat settable or heat annealable plastic insulating material into helical convolutions disposed along the length of said conductor, means for so controlling the formation of said convolutions that certain thereof are radially displaced from said conductor and the other convolutions engage said conductor at spaced points along the length of said conductor to support said certain convolutions from said conductor, and means for heating said filamentary element, thereby to cause permanent unstressed setting of said element in said convolution form.

6. Apparatus for making cable having an inner conductor, comprising a cylindrical convolution forming mandrel, means for continuously moving said conductor through said mandrel, means operated in timed relationship with said last-named means for continuously winding a continuous filamentary element of heat settable or heat annealable insulating material to form helical convolutions spaced along the length of said conductor and surrounding said conductor, means operated in timed relationship with said last-named means for so moving said mandrel that said convolutions are formed by wrapping said filamentary element alternately around said mandrel and directly around said conductor, whereby the convolutions formed by wrapping said element around said mandrel are radially spaced from said conductor and the convolutions formed by wrapping said element directly around said conductor serve to support said radially spaced convolutions from said conductor, and means for heating said mandrel, thereby to cause permanent unstressed setting of said element in said helical form.

7. The method of making cable having an inner conductor, which comprises feeding said conductor through a hollow cylindrical mandrel, wrapping a continuous filamentary element of insulating material around said mandrel to form helical convolutions spaced radially from said conductor, withdrawing said mandrel from said convolutions to space said convolutions along the moving conductor, wrapping said element around said conductor to support said convolutions, and continuously repeating the wrapping steps in the order named.

8. The method of making cable having an inner conductor, which comprises feeding said conductor through a hollow cylindrical mandrel, wrapping a continuous filamentary element of heat settable or heat annealable plastic insulating material around said mandrel to form helical convolutions spaced radially from said conductor, withdrawing said mandrel from said convolutions to space said convolutions along the moving conductor, wrapping said element around said conductor to support said convolutions, repeating said wrapping steps in the order named, and heating said mandrel and thus said material, thereby to cause permanent unstressed setting of said material in said convolution form.

9. Apparatus for making coaxial cable having

an inner conductor, comprising a cylindrical convolution forming mandrel, means for continuously moving said inner conductor through said mandrel, means operated in timed relationship with said last-named means for continuously winding a filamentary element of insulating material to form helical convolutions spaced along the length of said inner conductor and surrounding said inner conductor, means operated

5 in timed relationship with said last-named means for so moving said mandrel that said convolutions are formed by alternately wrapping said strip around said mandrel and directly around said inner conductor, whereby the convolutions formed by wrapping said strip around said mandrel are spaced radially from said inner conductor and the convolutions formed by wrapping said strip directly around said inner conductor serve to support said radially spaced convolutions from said inner conductor, and means for wrapping conducting material on said convolutions spaced radially from said inner conductor so as to produce an outer conductor.

10. Apparatus for making coaxial cable having an inner conductor, comprising means for continuously moving said inner conductor longitudinally thereof, means operated in timed relationship with said last-named means for continuously winding a filamentary element of insulating material around said inner conductor to form helical convolutions spaced around the length of said inner conductor and surrounding said inner conductor, means operated in timed relationship with said last-named means for so controlling the winding of said convolutions that certain thereof are radially displaced from said inner conductor and the other convolutions engage said inner conductor at spaced points along the length thereof to support said certain convolutions from said inner conductor, and means for wrapping a strip of conducting material around said certain convolutions radially displaced from said inner conductor to produce an outer conductor.

11. Apparatus for making cable having an inner conductor, comprising means for forming a continuous filamentary element of insulating material into helical convolutions disposed along the length of said conductor, means adapted to be operated in timed relationship with said last-named means for so varying the diameter of said convolutions that certain thereof are radially displaced from said inner conductor and others thereof engage said inner conductor at evenly spaced points along the length of said conductor, and means for operating said two last-named means while maintaining said predetermined timed relationship between the operations thereof.
